UNITED STATES PATENT OFFICE

139,602

DESIGN FOR A DIAGNOSTIC INSTRUMENT

Charles A. Ellis, Southbridge, Mass., assignor to
American Optical Company, Southbridge,
Mass., a voluntary association of Massachu-
sets

Application September 11, 1944, Serial No. 115,256

Term of patent 14 years

(Cl. D83—12)

To all whom it may concern:

Be it known that I, Charles A. Ellis, a citizen
of the United States of America, residing at
Southbridge, in the county of Worcester and
State of Massachusetts, have invented a new,
original, and ornamental Design for a Diagnostic
Instrument, of which the following is a specific-
cation, reference being made to the accompany-
ing drawing forming a part thereof.

Fig. 1 is a front elevational view of a diagnostic
instrument embodying the new design;

Fig. 2 is a side elevational view of the diagnostic
instrument shown in Fig. 1; and

Fig. 3 is a sectional view taken on line 3—3
of Fig. 1.

The characteristic features of the design re-
side in the portions shown in full lines in the
drawing.

I claim:

The ornamental design for a diagnostic instru-
ment, substantially as shown and described.

CHARLES A. ELLIS.
